UNITED STATES PATENT OFFICE.

JOSEPH B. ENTRIKIN, OF DES MOINES, IOWA.

RHEOSTAT.

SPECIFICATION forming part of Letters Patent No. 402,912, dated May 7, 1889.

Application filed January 22, 1889. Serial No. 297,171. (No model.)

To all whom it may concern:

Be it known that I, JOSEPH B. ENTRIKIN, a citizen of the United States of America, residing at Des Moines, in the county of Polk and State of Iowa, have invented certain new and useful Improvements in Rheostats, of which the following is a specification, reference being had therein to the accompanying drawing.

10 My invention relates to an improvement in apparatus for directing and controlling the strength of an electric current for mechanical purposes.

15 The object of this invention is to render useful as a motive power the current of electricity passing through the wires from an incandescent electric-light plant and dispense with the use and expense of a battery kept constantly charged; and the invention

20 consists in the particular construction and combination of devices that will be more fully set forth hereinafter, and particularly pointed out in the claims.

25 In the accompanying drawing is represented, partly in perspective and partly in section, an electric-current regulator constructed in accordance with my invention, and connected in circuit with an electric-light system and a mechanical tool, the latter being represented

30 by an electric dental mallet.

In said drawing, A represents a jar of suitable size, which is provided with a lid, B, and is partly filled with diluted acid solution, C. To protect the jar against breakage, it is preferably inclosed in a box, A², connected to the lid by straps a², hinged to said box. The lid B is made of insulating material—as hard rubber or wood—and has two vertical perforations, b, therein, through which loosely

40 pass two carbons, D, that are retained parallel to each other, and connected at their upper ends by a horizontal platform, E, of insulating material. To suspend the carbons D and their connecting-platform E at the proper height, a post, F, is secured vertically in the center of the lid and passes through the platform E, and the latter is adjustably connected with said post by means of a screw, e, inserted in the edge of said platform and having its

45 50 point bearing against the post F. Each carbon has its top provided with a binding-post, f, and screw f², to secure a wire thereto.

An electric current commonly used with an incandescent electric light, H², can be made to pass from the street-wires H to the wires G G², 55 and be regulated by the apparatus above described by connecting said wires with the posts f of the carbons D; but the main object of this invention being to render said current useful as a regulable motive power for mechanical purposes, the posts I are used. They have binding-screws i i², uniting the wires H to G G², and each one is also provided with binding-screws k k², to connect said posts with the operating-wires L L² of a mechanical device—as, for example, with an electric dental mallet, M, of ordinary form. The wires G G² and L L² are shown covered and united together a portion of their length; but it will be well understood that the wires forming a pair 70 are insulated from each other.

In using my invention, if it is desired to have the whole current used for operating the dental mallet or other mechanical device, the carbons are lifted clear off the solution. The 75 current then passes from one of the wires H to one of the binding-posts I, down the wire L to the mallet or other tool, and up the wire L² to the return-wire H; but if it is intended to diminish the strength of the current to be 80 used by the mallet, and consequently the strength of the blows given by the latter, the parallel carbons D are lowered the desired distance into the liquid. The tool acts then as a resistance, and a portion of the current 85 passes through the wires G G² and through the regulating device above described. A switch, S, is placed upon one of the wires H, to disconnect the tool from the electric light when desired.

Having now fully described my invention, I claim—

1. The electric-current regulator consisting of a vessel containing an acid solution, its lid having two vertical perforations, a central post secured to said lid, an insulating-platform adjustably secured to said post, two parallel carbons suspended from said platform and passing through the perforations in the lid, and binding-posts upon said carbons, substantially as described.

2. The combination of an electric-current regulator consisting of a vessel containing a chemical solution, its lid having two vertical

perforations, a central post secured to said lid, an insulating-platform adjustably secured to said post, two parallel carbons suspended from said platform and passing through the 5 perforations in the lid, and binding-posts upon said carbons, with electric wires connected to said carbons, binding-posts I upon said wires, a mechanical electric tool, and

wires connecting it with said posts I, substantially as described.

In testimony whereof I affix my signature in presence of two witnesses.

JOSEPH B. ENTRIKIN.
